ELECTRIC LOCK

William Wagner, Brooklyn, N. Y., assignor of
one-fifth to Clementine De Giuli, Brooklyn,
N. Y.

Application February 20, 1937, Serial No. 126,739

5 Claims. (Cl. 200—44)

This invention relates to electric locks, and has for an object to provide an improved construction which may be used in connection with various other objects to either throw a bolt for locking purposes or for properly connecting electrical circuits.

Another object of the invention is to provide an electric lock wherein an insulated key is used in connection with a cylinder for properly shifting the cylinder to secure a desired connection of two or more electric wires without producing a short circuit.

A further object, more specifically, is to provide an electric lock structure to be used in the ignition system of automobiles wherein either an insulated key is used or a key covered with insulating matter, with the parts so constructed that the key will actuate the usual tumblers to permit the cylinder of the lock to rotate and at the same time to provide a suitable switch connection.

In the accompanying drawing:

Fig. 1 is a side view of a lock disclosing an embodiment of the invention;

Fig. 2 is a sectional view through Fig. 1 approximately on the line 2—2;

Fig. 3 is a transverse sectional view through Fig. 1 approximately on the line 3—3;

Fig. 4 is a transverse sectional view through Fig. 1 approximately on the line 4—4;

Fig. 5 is a side view of the key illustrated in Fig. 2;

Fig. 6 is a longitudinal, horizontal, sectional view through a modified form of a key to that shown in Fig. 5.

Referring to the accompanying drawing by numerals, 1 indicates a casing having the usual cylinder 2. As shown in Fig. 2, there is a rear plate 3 secured to the rear end of the cylinder 2 by screw 4. However, if desired, this plate could be eliminated or an opening provided therein through which part or all of the cylinder 2 could project so as to be connected by a crank or other means to a bolt for throwing the same. However, as shown in the drawing, the device is especially adapted for an ignition lock for automobiles. The same structure could be used in connection with safes or other devices without departing from the spirit of the invention.

As shown in the accompanying drawing, the lock is provided with the usual tumblers 5 in the casing which are urged toward the cylinder 2 by the springs 6. In the cylinder 2 are arranged the usual cylinder tumblers 7 that are adapted to extend into the key slot or keyway 8, whereby the various cam portions 9 of the key 10 may

correctly position the tumblers 7 in order that the cylinder 2 may rotate. It will be observed particularly from Fig. 2 that the key 10 is made of insulating material and is provided with a pair of contact blocks 11 and 12 which are connected by a suitable conductor 13. This conductor may be wire, metal plate, or other member.

The cylinder 2 carries a pair of contact pins 14 and 15 made of metal and positioned to slide in an insulating sleeve provided with shoulders 31 and 32. These shoulders coacting with the heads 27 and 29 limit the inward movement of the respective pins. Springs 28 and 30 act on the respective heads 27 and 29 and on the respective pins 14' and 15' so as to urge the pins 14 and 15 inwardly. Pins 14' and 15' are mounted rigid or immovable in the insulation, but have their outer ends positioned to cooperate in the respective slots 17 and 18 with the contacts 19 and 20. Contact 19 is comparatively short, while preferably contact 20 is sufficiently long to remain in engagement with pin 14' at all times although this is not essential.

When the parts are in the position shown in Figs. 1 and 4, the circuit is broken, but when the cylinder 2 has been rotated until the pin 15' is in engagement with the insulated contact 19, the circuit will be closed through the conductors 21 and 22. These conductors form part of the ignition circuit and usually in one of these circuits is arranged a fuse so that in case anyone places a metal key into the key slot 8, the ignition circuit will be short circuited and the fuse will be blown.

Instead of having a key made from Bakelite, fiber, or other insulating material, it has been found that a metal key 23 may be used and formed with projections 24 and 25. The key 23 is completely covered by enamel or other insulating material 26, except the contact faces of projections 24 and 25 which engage the pins 14 and 15 when the key is in use. The general shape of the cylinder 2, the arrangement of the tumblers 5 and 7 and associated parts are all old and well known, but the remaining parts have been added to secure the results specified.

When the parts are in the position shown in Fig. 4, if a metal key was inserted and the cylinder turned until the pin 15' engaged contact 19, the wires of the circuit would be immediately grounded on the casing 1, which is naturally grounded on the automobile or on any other device to which the lock is connected. The combination of the various cams 9 of the key in connection with the tumblers may be varied in the

usual way well known to manufacturers of locks of this kind. In addition, the distance between the locks 11 and 12 may be changed, and when this is done the distance between the pins 14 and 15 must be changed. By making locks in these different ways a larger combination with different keys would be produced so that the liability of producing duplicate keys would be greatly reduced or eliminated.

10 I claim:

1. A lock of the character described including a casing, cylinder and tumblers, a pair of spaced pins carried by the cylinder but insulated therefrom, said pins extending into the keyway of the cylinder and to a position beyond the periphery of the cylinder, an insulated contact continually engaging one of said pins, an insulated contact positioned in the path of movement of the other of said pins, and a key of insulating material formed with a pair of electrically connected contacts adapted to engage one end of the respective pins carried by the cylinder when the key has been inserted sufficiently to rotate the cylinder.
2. In a lock of the character described, a metal cylinder, a casing around the metal cylinder, said casing and said cylinder having coating tumblers, said cylinder also having a keyway, a pair of contact pins insulated from the cylinder and extending from a point beyond the periphery to a point within said keyway, a resilient contact engaging one of said pins continually, a resilient contact spaced normally from the other contact, and a key having cam portions capable of adjusting said tumblers so that the cylinder may rotate, and a pair of connected contacts adapted to be brought into contact with said pins when the key has been forced into said keyway sufficiently to cause said tumblers to be moved to such positions that the cylinder may be rotated by the key.

3. In a standard cylinder lock, a cylinder provided with a keyway and a pair of pins extending from the keyway radially to a point beyond the periphery of the cylinder, said lock having a casing provided with a pair of slots into which said pins project, a contact member insulated from the casing and also from the cylinder, said contact being arc-shaped and continually in contact with one of said pins, a similar contact member for the other of said pins, said last mentioned contact being much shorter than the first mentioned contact and normally out of contact with its pin, and a key for turning said cylinder and said pins so that the respective pins will be in engagement with the respective contacts, said key being provided with means for properly shifting the tumblers in the lock, and a pair of connected spaced contacts positioned to engage the inner end of the respective pins for electrically connecting the same.

4. In a lock of the character described, a key formed of insulating material having embedded therein a conductor and a contact block at each end of said conductor, and a coacting lock provided with a cylinder having a pair of insulated radially extending pins adapted to engage said blocks when the key is in operative position, and a contact for each of said pins, one of said contacts being in continuous engagement with one of said pins and the other contact being engaged by the other pin only when the cylinder has been turned to an unlocked position.

5. In a lock of the character described, a casing, a cylinder, a key adapted to be inserted into the cylinder, said key having a pair of spaced electrically connected blocks, sliding means for connecting one of said blocks with a conductor, and a contact positioned in the path of movement of the other pin for electrically connecting the other pin with a second conductor.

40 WILLIAM WAGNER.
